STOCKING

Wasyl Trylowsky, 508 E. 5th St., New York, N.Y. 10009

Filed Jan. 31, 1968, Ser. No. 10,376

Term of patent 14 years

(Cl. D2—342)

The figure is a side elevational view of a stocking showing my new design, the side opposite that shown having no serpent design and being unornamented.

I claim:

The ornamental design for a stocking, as shown and described.
